DESIGN FOR A BOTTLE

Walter H. Meyer, Toledo, Ohio, assignor to National Nu Grape Company, Atlanta, Ga.

Application September 20, 1939, Serial No. 87,308

Term of patent 14 years

To all whom it may concern:

Be it known that I, Walter H. Meyer, a citizen of the United States, residing at Toledo, in the county of Lucas and State of Ohio, have invented a new, original, and ornamental Design for a Bottle, of which the following is a specification, reference being had to the accompanying drawing forming part thereof.

In the drawing:

I claim:
The ornamental design for a bottle, as shown.

WALTER H. MEYER.
